UNITED STATES PATENT OFFICE.

WILLIAM L. PAUL, OF BRADLEY, ILLINOIS, ASSIGNOR TO DAVID BRADLEY
MANUFACTURING COMPANY, OF BRADLEY, ILLINOIS, A CORPORATION
OF ILLINOIS.

PLOW.

SPECIFICATION forming part of Letters Patent No. 731,067, dated June 16, 1903.

Application filed August 11, 1902. Serial No. 119,249. (No model.)

To all whom it may concern:

Be it known that I, WILLIAM L. PAUL, a citizen of the United States, residing at Bradley, in the county of Kankakee and State of Illinois, have invented certain new and useful Improvements in Plows, of which the following is a specification, reference being had to the accompanying drawings.

My invention relates to plows; and its object is to provide new and improved means by which the plow may be "landed"—that is to say, may be made to take more or less land in width—by means of mechanism constantly within the control of the driver during the operation of plowing. I accomplish this object as hereinafter described, and as illustrated in the drawings.

That which I regard as new will be set forth in the claims.

20 In the drawings, Figure 1 is a side elevation, and Fig. 2 is a top or plan view.

Referring to the drawings, 3 indicates a frame, which is supported on land-wheel 4 and furrow-wheel 5. The frame 3 projects forward on the axle, hereinafter described, and is provided at its forward end with a clevis 30, to which the draft is applied for drawing the plow. The land-wheel 4 is carried by a bent axle 6, secured to the framework, and 30 is operated in any well-known and approved manner, as by means of a hand-lever 7 and rack-bar 8, to vary the depth of the cut. The furrow-wheel 5 is mounted in any well-known and approved manner upon the end of an axle 35 9 in such a way as to be raised and lowered thereon by means of the usual hand-lever 10 and rack-bar 11. The axle 9 is bolted or otherwise secured to the frame 3. As the means for raising and lowering the land and furrow 40 wheels may be of any approved form and description and are no part of my present invention, it is not necessary to describe them more fully here.

12 indicates a beam which carries the plow 45 13. 14 indicates a block, which is pivoted on a vertical pivot 15 between straps 16 at the rear end of the frame 3. The plow-beam 12 is bolted or otherwise secured to the block 14, thus forming a vertical pivot upon which the 50 plow-beam 12 may swing laterally from side to side.

17 indicates a rear caster-wheel, which is supported on a bent axle 18, carried by a bracket 19, which is bolted to the plow-beam 12 above the plow 13. The vertical portion 55 of the bent axle 18 is journaled in the rear end of the bracket 19 in order that the caster-wheel 17 may be moved to one side or the other in the usual manner.

20 indicates a seat, which is supported upon 60 a seat-beam 21, secured to the frame 3.

22 indicates a bell-crank lever, which is pivoted to a cross-bar 23 on the frame 3. The forward end of the bell-crank lever 22 is provided with a slot 24, which engages a pin 25, 65 secured to and projecting upward from the forward end of the plow-beam 12.

26 indicates a hand-lever, which is pivoted to the frame 3 and is provided with the usual rack-bar 27 and accompanying thumb-lever 70 70 and dog devices 28, which are adapted to lock the lever 26 in various positions on the rack-bar 27 and which operate in any well-known and approved manner.

29 indicates a link, one end of which is pivotally connected with the lever 26, near the lower end of said lever, and the other end is pivotally connected with the laterally-extending arm of the bell-crank lever 22. When the hand-lever 26 is swung forward or backward, the motion will be communicated to the bell-crank lever 22, and by means of the engagement of the slot 24 with the pin 25 the beam 12 and the attached plow will be swung laterally to one side or the other, according 85 to whether it is desired to make the plow take more or less land in width. If it is desired for any reason to have the plow take more land in width, the hand-lever 26 will be swung backward a suitable amount, thus throwing 90 the forward end of the plow-beam, and consequently the point of the plowshare, somewhat to the left, which will cause the point of the plow to bear into the landside of the furrow and take somewhat more land in 95 width. As the plow is pulled ahead by the horses, which are hitched to the clevis 30, it adjusts itself to the required conditions.

If it is desired to take less land, the hand-lever will be swung forward, carrying the forward end of the beam and the point of the plowshare somewhat to the right. 100

That which I claim as my invention, and desire to secure by Letters Patent, is—

1. In a plow, the combination with a frame, means for connecting said frame with the draft, of a beam not directly connected with the draft mounted on a substantially vertical pivot on said frame and adapted to swing laterally thereon, means for swinging said beam on its pivot, and a plow supported by said plow-beam, substantially as described.
2. In a plow, the combination with a frame, means for connecting said frame with the draft, and land and furrow wheels mounted on said frame, of a plow-beam not directly connected with the draft mounted on a substantially vertical pivot on said frame and adapted to swing laterally, means for swinging said plow-beam, and a plow mounted on said plow-beam, substantially as described.

3. In a plow, the combination with a frame, 20 means for connecting said frame with the draft, and land and furrow wheels supported by said frame, of a plow-beam not directly connected with the draft carried on a substantially vertical pivot on said frame and 25 adapted to swing laterally thereon, a plow carried on said plow-beam, a caster-wheel carried by said plow-beam, a bell-crank lever pivoted to said frame and having one of its arms pivotally connected with the forward 30 end of said plow-beam, a hand-lever pivoted to said frame, and a link connecting said hand-lever with the other arm of said bell-crank lever, substantially as described.

WILLIAM L. PAUL.
